US0D1109966S

(12) **United States Design Patent** (10) **Patent No.:** **US D1,109,966 S**
(45) **Date of Patent:** **** Jan. 20, 2026**

(54) **HOLDER FOR PHARMACEUTICAL GLOVES**

(71) Applicant: **SKAN AG**, Allschwil (CH)

(72) Inventors: **Freddy Thommen**, Basel (CH); **Dennis Balmer**, Basel (CH); **Andrew Richardson**, Michelbach-le-Haut (FR)

(73) Assignee: **SKAN AG**, Allschwil (CH)

(**) Term: **15 Years**

(21) Appl. No.: **29/943,499**

(22) Filed: **May 22, 2024**

(30) **Foreign Application Priority Data**

Dec. 20, 2023 (EM) 015045092

(51) **LOC (15) Cl.** **07-05**

(52) **U.S. Cl.** ..... **USPC D32/59**

CLAIM

The ornamental design for a holder for pharmaceutical gloves as shown and described.

DESCRIPTION

FIG. 1 is a perspective view of a holder for pharmaceutical gloves in accordance with our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 7 Drawing Sheets
